Charles A. Becker.

INVENTOR.
JOSEPH ABRAMOWITZ,
BY Ralph Taish
HIS ATTORNEY.

UNITED STATES PATENT OFFICE.

JOSEPH ABRAMOWITZ, OF NORTH VENICE, ILLINOIS, ASSIGNOR OF ONE-HALF TO JOHN SELB, OF VENICE, ILLINOIS.

COMBINED VENTILATING-INSOLE AND ARCH-SUPPORT FOR BOOTS, SHOES, AND THE LIKE.

1,160,810.

Specification of Letters Patent. Patented Nov. 16, 1915.

Application filed August 28, 1915. Serial No. 47,808.

To all whom it may concern:

Be it known that I, JOSEPH ABRAMOWITZ, a subject of the Czar of Russia, residing at North Venice, Madison county, State of Illinois, have invented a certain new and useful Combined Ventilating-Insole and Arch-Support for Boots, Shoes, and the like, of which the following is a specification, reference being had to the accompanying drawing, forming a part thereof.

My invention relates generally to footwear and, more particularly, to a certain new and useful combined ventilating insole and arch-support adapted to be positioned within a boot or shoe, the principal object of my invention being to provide a comparatively simple, inexpensive device which, in addition to serving as a support for a weakened instep or broken arch, performs the functions of an air-pump or bellows while the wearer of the shoe is walking, thus automatically ventilating the shoe, and which action tends to rapidly reduce, by evaporation, the natural perspiration of the foot, thereby maintaining the inner surface of the shoe and the combined pad and support in a comparatively dry condition.

A further object of my invention is to provide a device which, while forming a firm, substantial support for the arch or instep of the foot, is yielding and resilient to a certain degree, thereby automatically adjusting itself to the foot during service.

A further object of my invention is to provide a device of the class described, which can be easily and quickly applied to, or removed from, a boot or shoe.

With the above and other objects in view, my present invention resides in certain novel features of form, construction, arrangement, and combination parts, all as will herein-after be described and afterward pointed out in the claims.

In the accompanying drawing.—Figure 1 is an elevational view of a shoe, partly broken away, showing a combined ventilating pad and arch-support of my improved construction positioned for use in said shoe; Fig. 2 is a plan view of the combined pad and arch-support; Fig. 3 is a sectional view taken approximately on the line 3—3 of Fig. 2; Fig. 4 is a front elevational view of the combined pad and support; Fig. 5 is a sectional view taken approximately on the line 5—5 of Fig. 3; Fig. 6 is a plan view of the

device when constructed for use as a ventilating pad only; Fig. 7 is a sectional view taken on the line 7—7 of Fig. 6. Fig. 8 is a front elevational view of the ventilating pad; and Fig. 9 is a cross-sectional view taken on the line 9—9 of Fig. 7.

Referring by numerals to the accompanying drawing, and particularly to the form of device illustrated in Figs. 1 to 5 inclusive, 10 designates a base plate, preferably formed of thin sheet metal, such as steel, and applied to the under side of said plate is a section 11 of leather or analogous material. Formed in the front portion of the plate 10, by bending the metal of which said plate is formed, upwardly, is a plurality of longitudinally disposed ribs 12, see dotted lines in Fig. 2.

Positioned on top of plate 10 and bearing on the ribs 12, is a top plate 13, which is also formed of thin sheet metal, such as steel, and of the same size and shape as said plate 10, with the exception that it is provided on one side with a laterally projecting, upwardly curved portion 14, which, when the device is in use, lies immediately against the inner lower portion of the shoe upper and serves as a support for the arch or instep of the foot.

Interposed between the forward portions of the plates 10 and 13 and arranged between the ribs 12 is the forward portion of a flat spring 15, the rear portion of which bears against the underside of the rear portion of top plate 13. Rivets 16 or like devices pass through the forward portions of plates 10 and 13 and spring 15, thus serving to secure said parts firmly together.

The rear portions of plates 10 and 13 are separated or spaced apart a substantial distance, and interposed between said rear portions is one or more compression springs 17, the same being secured to either one or both of said plates. Thus it will be seen that the springs 15 and 17 yieldingly retain the plates 10 and 13 spaced apart from each other.

Positioned on top of plate 13 is a pad 18 of soft yielding material, such as wool-felt, and inclosing the entire device comprising the two metal plates, the underlying section of leather 11, and the top layer of cushioning material 18, is a cover 19 of thin flexible material, such as leather or water-proof fabric. It will be understood that the layered

padding and the section of covering material just referred to extend over the arch-supporting extension 14. The meeting edges of the cover 19 are secured to each other in any suitable manner, for instance, by stitching or by a suitable adhesive. Formed through the cover at the front edge of the device, and preferably at the forward end of the ribs 12, are openings 20, which serve as outlets for the air-space between plates 10 and 13. The device thus constructed is placed in the rear portion of the boot or shoe directly upon the insole with the arch-support lying immediately against the lower inner portion of the shoe-upper (see Fig. 1). Thus when the foot is placed in the shoe, the arch or instep of the foot is supported by the extension 14 and the entire heel-portion of the foot is yieldingly supported by the rear portion of the device, which, by virtue of its construction, including the springs described, serves as a pad or cushion. While the wearer of the shoe to which the device is applied is walking, the upper rear portion of the pad will be forced toward the lower rear portion, during which action the spring 17 will be compressed and the rear portion of spring 15 will be moved downwardly; such action necessarily expels the air from the space between the upper and lower parts of the device, such air finding exit in the spaces between the forward portions of plates 10 and 13 and through the openings 20. When the foot is lifted, as in taking a step, the springs within the device act to move the rear portions of the plates 10 and 13 apart, which action draws air into the air-space within the device through openings 20. Thus it will be seen that the device while in action performs the functions of a bellows or an air-pump, with the result that a circulation of air is produced in the lower portion of the shoe, consequently tending to reduce, by evaporation, perspiration of the foot and maintaining the support and pad in a comparatively dry condition. Inasmuch as the extension 14 is formed on top plate 13 and said top-plate is yieldingly forced upward under the influence of springs 15 and 17, said extension will be yieldingly maintained with a certain degree of upward pressure in proper position to support the arch or instep. The form of device illustrated in Figs. 6 to 9 inclusive is intended for use as a ventilating pad only, and this form of device is practically the same in construction as the combined pad and arch support herein described, with the exception that the underlying layer of leather 11, the top pad 18, and the arch-supporting extension are dispensed with.

A device of my improved construction is comparatively simple, can be easily and cheaply manufactured, can be readily positioned within or removed from a shoe, and in service provides an effective ventilating pad for the shoe, as well as forming a self-adjusting support for the arch or instep of the foot.

It will be readily understood that minor changes in the size, form, and construction of my improved device may be made and substituted for those herein shown and described without departing from the nature and spirit of my invention.

Having thus described my invention, what I claim and desire to secure by Letters Patent is:

1. In a device of the class described, a pair of plates spaced apart and secured to each other near one end, their other ends being free, a spring interposed between the free ends of said plates, and a cover inclosing said plates, there being openings in said cover communicating with the space between the attached ends of said plates.

2. In a device of the class described, a pair of plates secured to each other near one end, their other ends being free, ribs formed on one of the plates, which ribs serve as spacing means between the connected ends of said plates, a spring interposed between the free ends of said plates, and a flexible member inclosing said plates, there being openings formed in said inclosing member communicating with the space between the connected ends of the plates.

3. In a device of the class described, a pair of plates spaced apart and secured to each other near one end, their other ends being free, a spring interposed between the free ends of said plates, the upper plate having an outwardly projecting upwardly curved extension on one side, and a flexible member inclosing said plate and said extension, there being openings in said covering member which communicate with the space between the attached ends of said plates.

4. In a device of the class described, a pair of plates spaced apart and secured to each other near one end, their other ends being free, a spring interposed between the free ends of said plates, a layer of flexible material beneath the lower plate, the upper plate having an outwardly projecting upwardly curved extension on one side, and a flexible member inclosing said plates and the parts carried thereby, there being openings formed in said inclosing member communicating with the space between the connected ends of the plates.

In testimony whereof, I have attached my name to this specification.

JOSEPH ABRAMOWITZ.
